UNITED STATES PATENT OFFICE.

FRIEDRICH MÜLLER, OF NUERMBERG, GERMANY.

SMALL-SIZE BARREL ORGAN.

Application filed July 30, 1926, Serial No. 126,063, and in Germany November 14, 1924.

This invention relates to a small size barrel organ, which can be transported and played by any unskilled person by turning a handle.

5 The novelty consists in that the sound box as well as the wind box are horizontally arranged so that the sound box partly overlaps the wind box. This arrangement does not only permit of accommodating the whole 10 mechanism of the barrel organ in a small, oblong and low casing adapted to be carried on the shoulder by a strap but it permits also of simplifying the construction and of reducing the cost of manufacture.

15 An embodiment of the invention is shown, by way of example, in the accompanying drawing in which

Fig. 1 shows the improved toy-musical box in plan view.

20 Fig. 2 is a side elevation of Fig. 1.

Fig. 3 is a vertical section through the wind-box at the side of the worm-wheel driving the blade-shaft.

25 Fig. 4 is a vertical section through the sound-box and through the rear fork-shaped bracket for the crank-shaft.

Fig. 5 shows the fork-shaped bracket in elevation viewed from the inner side in the shape prior to the fixing on the circular 30 wall of the sound-box.

Fig. 6 is a section on line E—F of Fig. 4 showing how this circular wall is closed by the foot of this fork-shaped bracket.

The wind-box is built horizontally into 35 the sheet iron casing *l*, *k*, *i*, *3*, *4* and the vertical sound-box *a*, *c* is arranged under the perforated top-plate *b* of this sheet-metal casing in such a manner that its top plate *d* is situated in the same horizontal 40 plane as the bottom-plate *c* of the wind-box, the top plate and the bottom-plate being made of one piece of sheet-metal. In the wind-box *d* blades *z*, fixed on a vertical shaft *2*, are adapted to rotate, a worm *y* of wire being fixed by soldering on this shaft (Fig. 3). With this worm *y* gears a worm-wheel *x*, keyed on a crank-shaft *u* which is mounted in open slots *g'* of plates *g* of a bearing bracket and securely held in the 45 slots by a sheet-iron top-plate *w* fixed by flaps *w'* on the plate *g*. The whole apparatus is securely fixed in the sheet-metal casing by means of flaps *f* of the bottom-plate *c* of the wind-box and by means of 50 flaps *h* of the plate *g*.

The edges *a'* of the circular wall *a''* are covered by a sheet-metal-plate *v*, fixed by means of flaps *v'* on this circular wall. A zinc-disc *l*, having narrow slots *l'* rests upon a rib *9* on the inner surface of the wall *a''* (Fig. 4), reeds *m* being fixed by means of rivets *m'* under said slots *l'*. On the zinc-disc *l* rests a cardboard-disc *o*, which has radial slots *n* (Fig. 2) wider than the slots *l'* and than the reeds which fit almost accurately into the slots *l'*. A vertical pin 10 (Fig. 4) traverses the discs *l* and *o* at the centre. On this pin 10 a worm-wheel *q* of thin sheet-metal is mounted which has catch claws *r*, formed by flaps, bent downward from the spokes *s* and resting on the cardboard-disc *o*. A washer 12 on the pin 10 serves as abutment for a spiral-spring 12, wound around the pin and pressing upon the worm-wheel *q* so that the flaps *r* are 70 strongly pressed on the cardboard-disc, the head 14 on the lower end of pin 10 being thereby strongly pulled against the sound-disc *l*.

At the rotation of the worm-wheel the 80 cardboard-disc is also rotated and its slots *n* uncover gradually the slots in the zinc-disc so that air can pass through the slots *l'* and make the reeds *m* vibrate, whenever at the rotation of the cardboard-disc its slots 85 *n* come into register with the slots *l'*. The worm-wheel *q* is slowly rotated by the worm *p* on the crank-shaft *u*. For ensuring the correct engagement between the worm-wheel *q* and the worm *p* the crank-shaft is 90 mounted in front of and behind the worm in slots 14 of a fork-shaped bracket *t* (Figs. 2, 4 and 5). The transverse bars 15 which connect the one with the other the arms of the fork *t* have extensions 16, gripping from above and below over the rim of the worm-wheel to guide the same accurately along the central line of the worm. This bracket is made in one piece with the cover-plate *v*. 95

The object to save space in accommodating 100 the whole mechanism in a casing *i*, *3*, *k*, *4*, *b* which is similar to that of a barrel-organ, is thus obtained with the simplest and cheapest means. This casing can be easily carried on the shoulder by a strap 7 to be attached to 105 the upper edges of the end walls *3*, *4* at *5*, *6* so that the casing rests upon the left hip of the person who carries it. To operate the barrel organ the casing can be shifted to the front of the body so that a crank to be in- 110

serted at 8 (and which is not shown) can be turned.

The improved barrel organ can be used when the person who carries it is walking, 5 it can be transported in a travelling bag and it can be used also at home when placed on a table.

I claim:—

1. A small size barrel organ, comprising 10 in combination with a casing, a wind box horizontally mounted in said casing, a sound box developing a musical scale horizontally mounted in said casing partly on the top of said wind box, and an extension of the 15 top plate of said wind box forming the bottom plate of said sound box.

2. A small size barrel organ, comprising 20 in combination with a casing, a wind box horizontally mounted in said casing, a sound box developing a musical scale horizontally mounted in said casing partly on the top of said wind box, a sound disk in said sound box having sound slots, a cardboard disk on said sound disk and having slots for 25 alternately covering and uncovering said sound slots, a toothed driving wheel for slowly rotating said cardboard disk, a slotted bracket embracing and guiding the rim of said driving wheel, a driving crank shaft 30 journaled in said slotted bearing, a worm on said crank shaft inside said slotted bracket and meshing with said toothed driving wheel, a slit ring forming the wall of said sound box, and a plate rigid with said

slotted bracket and covering the edges of 35 said slit ring to close said ring.

3. A toy musical box, comprising in combination with a casing, a wind box horizontally mounted in said casing, a sound box horizontally mounted in said casing partly 40 on the top of said wind box, a sound disk in said sound box having sound slots, a cardboard disk on said sound disk and having slots for alternately covering and uncovering 45 said sound slots, a toothed driving wheel for slowly rotating said cardboard disk, a slotted bracket embracing and guiding the rim of said driving wheel, a driving crank shaft journaled in said slotted bearing, a worm on said crank shaft inside said slotted bracket and meshing with said toothed driving wheel, a slit ring forming the wall of 50 said sound box, a plate rigid with said slotted bracket and covering the edges of said slit ring to close said ring, wind vanes 55 in said wind box, a bracket on said wind box and consisting of two slotted side plates in the open slots of which said crank shaft is journaled, a cover plate of said bracket securely holding said crank shaft in the slots 60 of said side plates, and a driving wheel for said wind blades soldered upon said crank shaft outside said wind box.

In testimony whereof, I have signed my name to this specification at Nuremberg, 65 Germany, this 22nd day of June, 1926.

FRIEDRICH MÜLLER.
